UNITED STATES PATENT OFFICE.

TERENCE DOUGHERTY, OF BROOKLYN, NEW YORK.

RAILWAY-CAR FENDER.

1,253,014.

Specification of Letters Patent.

Patented Jan. 8, 1918.

Application filed September 6, 1917. Serial No. 190,008.

To all whom it may concern:

Be it known that I, TERENCE DOUGHERTY, a citizen of the United States, and a resident of the city of New York, borough of Brooklyn, in the county of Kings and State of New York, have invented a new and Improved Railway-Car Fender, of which the following is a full, clear, and exact description.

10 This invention relates to safety appliances for railway cars and has particular reference to fenders carried by the front ends thereof for the purpose of reducing the danger due to pedestrians who chance to be 15 in the path of movement of the cars.

More definitely stated one of the principal objects of this invention is to provide a fender for a railway car the same comprising relatively movable pad portions adapted 20 in one position to receive the impact of an obstacle on the track and reduce the extent of injury that would otherwise result from such occurrence, and in another position to be folded and housed beneath the platform 25 of the car.

Another object of the invention is to provide a fender having a substantially horizontal portion carried with its front end elevated from the track in position to be impacted against by an obstacle or person on 30 the track and so constructed that when so struck the front end thereof will automatically tilt down so as to facilitate the reception of the person or obstacle thereupon.

35 With the foregoing and other objects in view the invention consists in the arrangement and combination of parts hereinafter described and claimed, and while the invention is not restricted to the exact details of 40 construction disclosed or suggested herein, still for the purpose of illustrating a practical embodiment thereof reference is had to the accompanying drawings, in which like reference characters designate the same parts in the several views, and in which—

45 Figure 1 is a front perspective view showing my improvement in normal operative position.

Fig. 2 is a side elevation, parts being in 50 section, indicating the folded or nested position of the fender.

Fig. 3 is a vertical longitudinal section 55 showing the parts in full lines in the position of Fig. 1 and indicating in dotted lines the dropped position of the platform pad and apron.

Fig. 4 is a sectional detail on the line 4—4 of Fig. 3; and

Fig. 5 is an enlarged vertical sectional detail through one front corner of the device, 60 the plane of the section being parallel to the direction of movement of the car.

In carrying out this improvement in a practical form I provide a fender comprising two main pad or upholstered portions 10 and 11, the former being adapted to be carried in operative position in a substantially vertical plane on or in front of the car where it will be supported by means of a hook 12 or its equivalent coöperating with 65 the sill 13 at the front end of the car platform 14. The other pad is hinged at 15 on the front ends of a pair of channel bars 16 70 slide longitudinally along a pair of fixed bars 17 suspended upon pairs of hangers 18 75 on the opposite sides of the car each having a hooked shaped lower end 18' as indicated in Fig. 4. The axis of the hinge 15 is arranged just back of the transverse center of the pad 11 so that when the rear end or 80 edge of the pad 11 is not supported the front end of the pad will drop freely until it strikes the track or a pair of rollers 19 dropped upon the rails 20 of the track bringing the front end of the pad well down so as 85 to facilitate the delivery upon the pad of the person or other object that is struck.

As will be noted especially in Fig. 3 the rear end of the pad 11 is supported directly upon the upper faces of the channel bars 16 90 and is held in such position by means of toggle links 21 jointed together at 22 and having their opposite ends pivoted to the adjacent edges of the two pads 10 and 11, the pad 10 being elevated at this time directly above the rear edge of the horizontal pad and separated therefrom by a space equal to the length of the toggle links when extended. A spring 23 connected at its rear end at 24 to the channel bar 16 and at its 100 front end to the pivot 22, serves to hold the toggle link straight and bearing against a lug 25, or its equivalent, carried by the upper pad which serves to prevent the rearward movement or buckling of the toggle link. 105 The upper pad 10 is braced at its lower edge by means of a bar 26, the upper or rear end of which is connected to a sprocket chain 27 operating in a horizontal plane just beneath the platform 14 and over the sprocket wheels 110 28 and 29, the latter wheel being connected to a vertical crank shaft 30 having a handle

or crank 31 at its upper end for manipulation.

Any suitable means such as a pawl or ratchet device 32 may be employed to hold 5 the crank shaft 30 from rotation and thus the brace rod 26 is normally held in fixed position. While the springs 23 act normally to hold the links 21 in straight vertical position against the lugs 25 the reaction of the 10 springs acting through the bars 16 tends to hold the horizontal pad 11 projected forwardly. If now an obstacle be struck by the front end or edge of the pad 11 at least two immediate results take place, namely, 15 the pad as a whole is forced rearwardly slightly, such impact being cushioned by the springs 23 and this fact in itself constitutes a safeguard to a certain extent. As a second result of this impact of the rearward movement 20 of the pad 11, the joint at 22 is broken permitting the pad 11 to tilt downwardly in front and upwardly at the rear as indicated in dotted lines in Fig. 3. Thus will the person or other object on the track be delivered 25 directly upon or within the fender.

33 indicates an apron secured permanently at its upper edge to the pad 10 and having detachable snap connection at 34 at the front corners of the pad 11. This apron constitutes 30 a cover or protector for the upholstered portions of the device whereby rain, dirt, dust or the like will be practically kept therefrom. The sides of the fender are inclosed by fixed triangular aprons 35 held permanently 35 in position along the sides of the right angle upon the edges of the pad 10 and apron 33. The aprons 35 being relatively thin and flexible and having practically negligible thickness will simply collapse 40 or fold and lie between the two pads 10 and 11 when the fender is collapsed as in Fig. 2.

In the practical operation of this improvement if an obstacle or person is struck 45 by the front edge of the pad 11 causing the pad to move relatively rearwardly, this movement will cause the breaking of the toggle and permit the tilting downwardly of the front end of the pad. It will, of course, be understood that the impact of the 50 object against the apron 33 will detach the same from the fasteners 34 so as not to prevent the downward tilting movement of the pad. The pad 11 may easily be restored to 55 its normal horizontal position either by lifting up on the front end thereof or the action of the springs 23 straightening and locking the device at the toggle links.

When it is desired to collapse or retract 60 the fender the vertical pad 10 is released at

the hook 12 so as to be free to tilt downwardly when the chain 36 is paid out from the drum 37 mounted upon the crank shaft 30. The drum and its connection with the upper end of the pad 10 may be so designed as to harmonize with the operation of the chain 27 which will bring the link 26 and lower end of the pad 10 rearwardly along with the lower pad while the channel bars 16 slide rearwardly over the fixed bars 17 to the position indicated in Fig. 2 and at which time the whole fender will be nested beneath the platform 14. Obviously a reverse movement of the crank shaft will cause the projection forwardly of the fender and 75 the elevation of the pad 10 to its operative position.

I claim:

1. In a fender for railway cars, the combination of a plurality of pads arranged 80 normally at an angle to each other, toggle link devices connecting the adjacent edges of the pads, means pivotally supporting the lower pad providing for tilting movement thereof downwardly in front and out of normal horizontal position when the toggle links are broken, and means acting upon the toggle links to hold them rigid preventing the tilting of the lower pad.

2. In a railway car fender, the combination of an upright pad, means to hold the same in upright position, a normally horizontal pad, toggle links connecting the adjacent edges of the two pads, said toggle links being adapted to break forwardly, the spring 90 acting upon the joint of the links to hold them stiff, and means to cause the toggle links to break against the force of the springs when the lower pad strikes an obstacle thereby permitting the lower pad to 95 tilt downwardly at its front end.

3. The combination with a car platform and pairs of hangers projecting therefrom, of a horizontal bar mounted upon each pair of hangers, a channel bar slidable upon each horizontal bar, a pad pivotally connected to the front ends of the channel members, and means acting upon the pad to draw the same and the channel members rearwardly or forwardly along the first mentioned bars.

4. In a fender for railway cars, the combination of a pad, an endless power element movable in a horizontal plane at the rear of said pad, a bar extending between the power element and the pad, and means to operate the power element from the platform so as to draw the pad rearwardly beneath the platform or move it forwardly into operative position.

TERENCE DOUGHERTY.
